UNITED STATES PATENT OFFICE.

OSCAR P. BREITHUT, OF PORTLAND, OREGON.

GAME-BOARD.

1,096,823.

Specification of Letters Patent. Patented May 19, 1914.

Application filed April 24, 1912. Serial No. 692,881.

To all whom it may concern:

Be it known that I, OSCAR P. BREITHUT, citizen of the United States, residing at Portland, in the county of Multnomah and 5 State of Oregon, have invented certain new and useful Improvements in Game-Boards, of which the following is a specification.

This invention relates to game apparatus, and has as its object to provide a gameboard 10 upon which a highly interesting game may be played resembling to a certain extent, the games of billiards and pool.

The invention aims among other things to provide a gameboard, the game to be 15 played upon which will require considerable skill on the part of the players.

The gameboard embodying the present invention is of that type having a surface over which game projectiles are to be propelled 20 and which embodies pockets and side and end cushions extending between the pockets, and one feature of the invention resides in so constructing the cushions that they may be manufactured at a low cost and yet will 25 be sufficiently "lively" to permit of difficult cushion shots being made.

Another feature of the invention resides in the provision of means for preventing the projectiles jumping the table.

For a full understanding of the invention 30 reference is to be had to the following description and accompanying drawing, in which:—

Figure 1 is a perspective view of the game- 35 board or table embodying the present invention. Fig. 2 is a vertical longitudinal sectional view through the cue constituting a part of the game apparatus. Fig. 3 is a horizontal sectional view on the line 3—3 40 of Fig. 1.

Corresponding and like parts are referred to in the following description and indicated in all the views of the accompanying drawing 45 by the same reference characters.

In the accompanying drawings, the base 50 or bottom of the gameboard or table is indicated by the numeral 1, its upper face constituting the surface over which the game projectiles are to be propelled. Rails 2 up- 55 stand from the bottom 1 at the lateral edges thereof and rails 3 extend above the surface of the bottom 1 at the end-edges thereof.

The table may be supported upon legs 4 or it may be disposed upon another table or 55 any other suitable support, depending chiefly upon the dimensions of the table. The bot-

tom of the board has its playing surface cut away at each corner of the table to form pockets 5 and similar pockets 6 are provided at each side of the table at a point midway 60 between the pockets 5.

A cushion is mounted upon each of the rails 3 and extends between the corresponding corner pockets 5 and similar cushions are mounted on the side rails 2 and extend 65 between the said corner pockets and the side pockets 6. Each of the rails above referred to is in the form of a length of resilient wire indicated at 7 and having its ends bent to form eyes 8. Screws or bolts 9 are secured 70 through the eyes 8 and into or through the rail 2 and 3 upon which the cushion is supported. The wire comprising each of the cushions above referred to is bent at an angle 75 as at 10 between its intermediate portion and each of its terminal eyes 8 so that when the cushion is secured in place upon the respective rail the intermediate portion of the wire forming the cushion will be spaced from the inner face of the rail.

The game-pieces or projectiles which are to be propelled across the board or table are in the nature of flat-sided circular disks 11 of which there are sixteen, each of these disks having upon its upper face a numeral 12 denoting its value as a game-piece. There is also provided a disk 13 which in size and shape corresponds to the disk 11 and this disk 13 is designed to serve the same purpose as the cue ball in a game of billiards 90 or pool.

In order to prevent the game-pieces or projectiles 11 from jumping the table, which would be likely to occur if a hard shot were made, guard rails are mounted one at each 95 side of the table and one at each end thereof and are so mounted that while normally they are out of the way of the players using the table they may be readily swung up so as to perform the function stated.

Each of the end-rails is indicated by the numeral 14 and is secured at its ends to the free ends of arms 15 which are pivoted by means of a bolt 16 to the side rails 2 at points adjacent their ends. The pivot 16 for 105 each of the arms 15 passes through a concavo-convex washer 17 which is resilient and which serves to also frictionally bind the pivoted ends of the arms 15 as to hold these arms in upright position when the rail 14 110 is in use.

By referring to Fig. 1 of the drawing it

- will be observed that when either end rail is in use, the arms 15 stand substantially vertically and the rail extends above the end-cushion 7. When these rails are not in use, 5 the arms 15 are swung outwardly and downwardly so as to position the rail supported thereby beneath the lower edge of the respective end-rail 3. Each of the side guard rails is indicated by the numeral 18 and is 10 supported by the pivoted arms 19 corresponding to the arms 15. These arms 19 are pivoted at their ends to bars 20 secured one upon each of the side rails 2. When the rails 18 are not in use they lie beneath the 15 respective bars 20 but when it is desired to use this rail at either side of the table, the same is swung up to assume about the position assumed by the elevated rail 14 in Fig. 1 of the drawing.
- 20 The cue embodying the present invention and illustrated in Fig. 2 of the drawing includes a tubular body 21 having one end reduced as at 22. A rod 23 having a tip 24, is slidably mounted in the body 21 and a spring 25 upon this rod bears at one end against the inner end of the tip 24 and at its other end against the shoulder formed in the reduced end 22 of the said tubular body. The rod 23 is provided at its end opposite the end at which the tip 24 is located with a handle 26 and in using the cue the handle 26 is grasped and the rod 23 is pulled rearwardly whereby to retract the tip 24. The end of the tip 24 is then placed in close 35 proximity to the game-piece to be propelled and the handle 26 is released. The spring 25 will then act, as will be readily understood, to forcibly propel the projectile across the surface of the table.
- 40 In using the game apparatus herein described the game pieces 11 are arranged in two rows extending across the table substantially on a line between the ends of the side pockets 6. In so arranging the game-pieces 45 no care is taken to place them with the

numbers thereon in any particular order. After the game-pieces 11 have been properly arranged, the game-piece 13 is disposed about in the position shown in Fig. 1 of the drawing and is propelled by the use of the 50 cue shown in Fig. 2 against one or the other of the cushions 7, as indicated in dotted lines in Fig. 1 of the drawing. If the player is skilful the game-piece 13, in rebounding from the side cushion 7 after it 55 has been propelled, will strike one or another of the game-pieces in the adjacent row and drive it or another of the pieces into one of the pockets. Should the player succeed in pocketing one of the game-pieces, he 60 is allowed a second shot. Should the player fail to make the attempted shot, the next player will attempt such a shot as he may desire to make and after the second player has finished his play, the first player will 65 again attempt to play the object piece in one or another of the pockets.

It will of course be understood that the manner of playing the game may be varied and that the game apparatus may be used 70 in playing various games resembling billiards or pool.

Having thus described the invention what is claimed as new is:—

In a game apparatus of the class described, a game board having a banking rail, arms swingingly mounted one at each end of the rail, and a guard rail secured between the free ends of the arms, said arms being so proportioned that in one position 80 the guard rail lies beneath and forms a continuation of the main rail, while in the other position it extends above and forms a continuation of the main rail.

In testimony whereof I affix my signature in presence of two witnesses.

OSCAR P. BREITHUT. [L.S.]
